DISPENSING HEAD FOR A PRESSURE CONTAINER

Robert Stephen Schultz, Somerville, N.J., assignor to
American Can Company, New York, N.Y., a corporation of New Jersey

Filed Aug. 30, 1963, Ser. No. 76,418

Term of patent 14 years

(Cl. D58—26)

Fig. 1.

Fig. 4.

Fig. 3.

Fig. 2.

FIGURE 1 is an elevational view of a dispensing head for a pressure container embodying my new design;

FIGURE 2 is a top plan view thereof;

FIGURE 3 is an elevational view thereof; and

FIGURE 4 is a perspective view thereof.

The portions shown in broken lines are for illustrative purposes only.

I claim:

The ornamental design for a dispensing head for pressure container, substantially as shown and described.
